UNITED STATES PATENT OFFICE

HERMAN RYNVELD, OF NEW YORK, N. Y.

DESIGN FOR A PACKAGE CARTON OR SIMILAR ARTICLE

Application filed April 21, 1932. Serial No. 43,566. Term of patent 3½ years

To all whom it may concern:

Be it known that HERMAN RYNVELD, a subject of the Kingdom of Holland, and resident of New York city, in the county of New York and State of New York, has invented a new, original, and ornamental Design for a Package Carton or Similar Article, of which the following is a specification, reference being had to the accompanying drawing, forming part thereof, in which,

The figure is a perspective view of a package carton embodying my new design, the portion A being lined for blue and the showing of portion B, being intended to indicate that same is transparent.

I claim:

The ornamental design for a package carton or similar article, substantially as shown and described.

Dated, April 19, 1932.

HERMAN RYNVELD.
